Townsend & Wecker.

UNITED STATES PATENT OFFICE.

PETER JOHN KURSCHEIDT, OF BROOKLYN, NEW YORK, ASSIGNOR TO PERFECT WINDOW REGULATOR COMPANY, OF NEW YORK, N. Y., A CORPORATION OF MAINE.

ADJUSTABLE STOP FOR WINDOW REGULATORS.

Application filed February 27, 1922. Serial No. 539,371.

To all whom it may concern:

Be it known that I, PETER JOHN KURSCHEIDT, a citizen of the United States, and a resident of Brooklyn, in the county of 5 Kings and State of New York, have invented certain new and useful Improvements in Adjustable Stops for Window Regulators, of which the following is a specification.

My invention relates to window regulators or lifts for raising or lowering a window and it is particularly adapted for use in that type of regulators now well known in the art and employing two sprockets or other rotatable members, a chain or other 10 linear member running thereover, a handle or other means for rotating the sprockets and a connection between the chain and the window whereby the window is raised or lowered as desired upon rotation of the 15 handle.

The principal object of the invention is the production of a novel and simple stop which may be detachably connected to the chain and by means of which the window 20 is prevented against further movement in the same direction after it has reached any given position.

Other and further objects and advantages of the invention will appear from the 25 accompanying description, the invention consisting in the novel parts and combinations thereof hereinafter more particularly described and then specified in the claims.

In the accompanying drawing showing a 30 practical embodiment of the invention:

Fig. 1 is a front elevation of a window regulator showing my invention in conjunction therewith.

Fig. 2 is a side elevation of a portion of 40 the chain with the adjustable stop detachably fastened thereto.

Fig. 3 is a vertical cross-section on the line 3—3 of Fig. 2.

Fig. 4 is an end view of the stop.

Fig. 5 is a front elevation of a modification.

Fig. 6 is a vertical cross-section on the line 6—6 of Fig. 5.

Referring to the drawing:

1 indicates a window which is adapted to be reciprocated vertically in a suitable frame

the lower part of which is indicated at 2. A plate 3 is secured to the frame 2 and is provided with an upper sprocket 4 mounted thereon. 5 indicates a bar or strap which 55 is fastened to the plate 3 and on which a lower sprocket 6 is mounted. The bar or strap 5 is held against movement by a cross-bar 7 secured thereto, the ends of said cross-bar being fastened to the frame of the window 60 well or other support.

8 indicates an endless chain which passes over the sprockets 4 and 6, the links of said chain being provided with slots 9 extending therethrough. A roller stud support 10 65 provided with an extension 11 is fastened to said chain and carries a roller stud 12 engaging in an open slot 13 of a plate 14 which is fastened to and depends downwardly from the lower edge of the window 70 1. By rotating a handle 15 which is operatively connected with the upper sprocket 4 the chain is caused to travel around the sprockets 4 and 6 and the window is thus raised or lowered according to the direction 75 of rotation given the handle in an obvious manner now well known and requiring no detailed description.

When the window has reached its extreme uppermost position it is desirable to provide 80 some positive means which will prevent a further movement of the window otherwise a continued rotation of the handle 15 would be apt not only to tilt the window but in some cases to force the roller stud 12 completely out of the slot 13. Accordingly I have provided the plate 3 with a projection 85 16 which preferably is a portion of the material of the plate itself cut out and bent over in a plane transverse to the plane of the plate. When the window has reached its upper or closed position the extension 11 of the roller stud support 10 engages the projection 16 as shown in Fig. 1 and further movement of the handle or window in the 90 same direction is thereby prevented.

It is also desirable to provide some means for preventing a forcing of the stud 12 out of the slot 13 if rotation of the handle in the same direction is attempted after 100 the window has been opened or has reached its lower position. This is accomplished

by the provision of an adjustable stop shown in detail in Figs. 2, 3 and 4. This stop comprises a head 17 and spring arms 18 preferably integral therewith, said parts forming a U-shaped member. The arms 18 are provided with side flanges 19 and 20 which may be integral therewith and which are bent over in parallelism and at right angles to the arms as shown in Fig. 3. The ends of the arms are bent inwardly to form gripping members 20' adapted to engage within the slots 9 of any of the links of the chain. To mount the stop on the chain the arms are spread apart and the members 20' inserted in the slots 9 of one of the chain links. A screw 21 is then threaded through suitable openings in the flanges 19 and 20 which, as is obvious, keeps the arms from spreading outwardly and prevents removal of the members 20' from the slots 9 until the screw is removed. Inasmuch as said members interfit snugly with said slots a rocking of the device on the chain is prevented. When the stop is applied to the proper link the end of the screw will strike the projection 16 of the plate 3 as shown in dotted lines in Fig. 1 and thereby prevent a further downward movement of the window or a rotation of the handle in the same direction.

Inasmuch as the stop may be applied to any link of the chain it is obvious that it may be positioned so as to function when the window has been partially opened only 35 or before it has reached its extreme lower position. If a finer adjustment is desired than can be obtained by shifting the stop from one link to another this may be secured by screwing the screw 21 further through the flanges 19 and 20 or unscrewing the same so as to vary the distance between the end of the screw and the projection 16. The tendency of the spring arms 18 to spread outwardly, moreover, 40 serves to securely hold the screw in any desired adjusted position without the necessity of employing an additional lock nut.

In the modification illustrated in Figs. 5 and 6 the chain links are provided with 50 annular openings 22 extending therethrough instead of with slots as in the preferred form of the invention. These openings are adapted to receive lugs pressed in the lower portions of the spring arms of the stop. 55 When the modified device is in position on one of the chain links the lower edges of the flanges 19, 20 seat on or just clear the top of the chain link to prevent rocking of the stop.

60 What I claim as my invention is:—

1. In a window regulator, a sprocket, a chain running thereover for transmitting motion to the window, a projection and a stop detachably fastened to said chain and 65 adapted to engage said projection for pre-

venting movement of the window beyond any given predetermined position in its travel.

2. In a window regulator, a sprocket, a chain running thereover for transmitting motion and provided with a plurality of slots therein at spaced intervals, a projection and a detachable stop engaging within a slot of said chain and adapted to engage said projection for preventing movement of the window in one direction. 75

3. In a window regulator, a sprocket, a chain running thereover for transmitting motion to the window, a projection and a detachable stop adapted to engage said projection for preventing movement of the window in one direction, said stop being provided with spring arms gripping the chain and means for holding said arms in gripping engagement. 80

4. In a window regulator, a sprocket, a chain running thereover for transmitting motion to the window, a projection and a stop, said stop having arms detachably gripping the chain and a member carried by said stop adapted to engage said projection for preventing movement of the window in one direction. 85

5. In a window regulator, a sprocket, a chain running thereover for transmitting motion to the window, a projection and a stop, said stop having arms detachably engaging the chain and a screw carried by said stop adapted to engage said projection for preventing movement of the window in one direction. 95

6. In a window regulator, a sprocket, a chain running thereover for transmitting motion to the window, a projection and a stop, said stop having arms detachably engaging said chain and a screw carried by said stop adapted to engage said projection for preventing movement of the window in one direction, said arms acting to resist a movement of said screw. 105

7. In a window regulator, a sprocket, a chain running thereover for transmitting motion to the window and provided with slots therein, a projection and a stop, said stop having arms entering said slots and a screw for holding said arms within said slots and adapted to engage said projection to prevent movement of the window in one direction. 115

8. In a window regulator, a sprocket, a chain running thereover for transmitting motion to the window, a projection and a stop, said stop having spring arms detachably connected to said chain, flanges on said arms and a screw threading through said flanges for holding said arms in engagement with said chain and adapted to engage said projection to prevent movement of the window in one direction. 120

9. In a window regulator, a sprocket, a 125

chain running thereover for transmitting motion to the window, a projection and a stop, said stop being adapted to engage said projection to prevent movement of the window in one direction and comprising a U-shaped member having arms detachably connected to said chain and means for holding said arms in connected position.

Signed at New York in the county of New York and State of New York this 25th **10** day of February A. D. 1922.
